SPLIT-PHASE MOTOR CONTROL

George C. Pearce, Dayton, Ohio, assignor to General Motors Corporation, Dayton, Ohio, a corporation of Delaware

Application January 31, 1939, Serial No. 253,828

1 Claim. (Cl. 172—279)

This invention relates to refrigerating apparatus and more particularly to control means for controlling single phase, alternating current, electric motors.

In refrigerating systems and other installations it is customary to provide a thermostatic switch for starting and stopping the motor which drives the compressor and an electro-thermal or electromagnetic starting relay which controls energization and deenergization of the starting winding of the motor. This second control is independent of the thermostat control excepting that it is operated electrically when the thermostat energizes the motor circuit. Thus a dual control has been necessary for such systems. In such a system, the snap action provided in the thermostat is somewhat noisy and in addition the electromagnetic or the electro-thermal starting relay are also somewhat noisy.

It is an object of my invention to provide a simplified control for refrigerating systems and other installations in which the thermostat directly controls the energization of both the starting and the running windings.

It is another object of my invention to provide a pressure operated control in which the movement provided by the pressure operated means operates the contact means for controlling the energization of both the starting and running windings.

It is another object of my invention to provide a control in which the force provided by the pressure operated means furnishes the power for closing and opening both the starting and running winding circuits of the electric motor.

It is still another object of my invention to provide a control which is very silent.

Further objects and advantages of the present invention will be apparent from the following description, reference being had to the accompanying drawing, wherein a preferred form of the present invention is clearly shown.

In the drawing:

Fig. 1 is a view partly diagrammatic showing a refrigerating system and a control therefor embodying my invention;

Fig. 2 is a sectional view of the mercury tube in the "off" position;

Fig. 3 is a sectional view of the mercury tube when tripped to starting position; and

Fig. 4 is a sectional view of the mercury tube showing conditions prevailing during the running period.

Briefly, I have shown a refrigerating system provided with a thermostat control which op-

erates a tilting mercury tube. This tilting mercury tube has a contact at one end connecting with one end of the starting winding and a pair of contacts at the other end, one of which is connected to a source of power and the other of which is connected to the common terminal of the starting and running windings. In the middle of the mercury tube, between the contacts at either end of the tube, there is provided a dam having an orifice therein. When the mercury tube is tilted to the position shown in Fig. 2, no current flows because none of the sets of contacts are bridged. However, when the mercury tube is changed from the position shown in Fig. 2 to the position shown in Fig. 3 all three of the contacts are bridged by the mercury so that both the starting and running windings are energized. However, after the mercury tube remains in the position shown in Fig. 3 for a short time the mercury runs to one end of the tube, as shown in Fig. 4, so that the long contact which connects to the starting windings is no longer contacted by the mercury and in this way the starting winding is deenergized. The length of time the starting winding is energized is determined by the size of the orifice.

Referring now to the drawing and more particularly to Fig. 1, there is shown for the purpose of illustrating my invention, a refrigerating system including a compressor 20 for compressing refrigerant and for forwarding the compressed refrigerant to a condenser 22 where the condensed refrigerant is liquefied and collected in a receiver 24. From the receiver the liquid refrigerant is forwarded under the control of a suitable expansion device 26 such as an expansion valve or restrictor to an evaporating means 28 located within the compartment 30 to be cooled. The refrigerant evaporates within the evaporating means 28 under reduced pressure and absorbs heat from the air or fluid within the compartment 30. This evaporated refrigerant is returned to the compressor through the return conduit 32. The compressor 20 is driven by an electric motor 34 shown diagrammatically. This motor 34 is shown as of the split phase type having starting winding 36 and a running winding 38. Instead of the split phase type a capacitor start motor having a capacitor connected in series or parallel with the starting winding 36 may also be used in conjunction with the control herein disclosed.

Heretofore it has been customary to provide a thermostat in series with the running winding 38 and to provide an electrically operated elec-

tromagnetic or electrothermal relay which is operated by the current flowing through the running winding 38 for operating contacts for controlling the energizing of the starting winding 36. There has always been some difficulty with these relays, particularly because of fluctuating voltage conditions and different voltage conditions existing in different communities and even in different portions of the different communities. It has therefore been necessary to provide voltage compensating devices or other protective devices to accommodate the various voltage conditions to which the motor may be subjected. These starting devices require a certain amount of energy for their operation and are also somewhat noisy and troublesome.

In order to overcome these difficulties I have provided a mercury tube type of contact mechanism which not only controls energization of the running winding but also controls the energization of the starting winding. The mercury tube controls are in themselves substantially noiseless and trouble free. They are sealed so that there is practically no contact trouble. By my improved arrangement only one tube is required for controlling both windings.

In my arrangement one of the sources of power is connected by conductor 42 to the contact 44 within the sealed glass mercury tube 46 which forms a part of the thermostat control 48 for the refrigerating system. One end of the running winding 38 and one end of the starting winding 36 are connected together and this connection is in turn connected by the conductor 40 to the other lines of the source of power. The other end of the running winding 38 is connected by the conductor 50 to a winding which is coiled about a ratchet wheel type of solder pot overload as designated by the reference character 52 which, in turn is connected by the conductor 54 to a second contact 56 within the mercury tube 46. The contacts 44 and 56 are in one end of the tube while the third contact 58 extends to the opposite end of the tube and has its end portion turned downwardly.

Near the middle of the tube is provided a dam 60 which may be formed of glass or metal fused into the glass walls of the tube. This dam is located between the turned down end of the contact 58 and the contacts 44 and 56. This dam is slanted so as to force the mercury to flow through an orifice 62 in moving from the end where the contact 58 is located to the opposite end where the contacts 44 and 56 are located. This orifice holds some of the mercury in contact with the contact 58 for a brief period of time so that all the contacts are bridged by the mercury as shown in Fig. 3. During this brief period of time the motor will start upon both windings and within a short time the level of mercury will recede from the level shown in Fig. 3 so as to de-energize the starting winding. The mercury finally assumes the position shown in Fig. 4 in which only the contacts 44 and 56 are bridged, thereby keeping the running winding 38 energized.

The mercury tube 46 is supported by a spring clamp at its center portion, which extends from a lever and bracket member 64, pivotally mounted upon the threaded pin 66 which is threaded into the pivot support member 68. The member 64 is provided with stop projections 70 and 72 which engage the sides of the pivot support 68 to limit the tilting movement of the mercury tube 46 in either direction. The stop 70 limits the move-

ment of the mercury tube to the angle shown in Figs. 3 and 4, while the stop 72 limits the movement of the tube to the angle shown in Fig. 2. In order to provide a snap action so that a differential may be provided between starting and stopping, the member 64 is provided with a pin 74 at its upper end to which is connected a light tension toggle spring 76 having its lower end connected to a pin 78 formed on the pivot bracket 68.

The member 64 is also provided with a lever arm 80 having its end portion connected by a link 82 to the end of a primary lever 84 pivotally connected by the threaded pin 86 to an upwardly extending arm 88 of the switch frame. The switch frame is also provided with a base portion 90 upon which is mounted a metal bellows 92 having a pin on its upper end which engages the primary lever 84. This bellows 92 is connected by capillary tubing 94 to a thermostat bulb 96 mounted upon the evaporating means 28. This bulb 96 may be charged with a volatile fluid so that the pressure within the bellows 92 will correspond with the temperature of the evaporating means. However, if desired, the bulb 96 may be placed out of contact with the evaporating means, but within the compartment 30 so that it will be responsive to the temperature of the fluid in the compartment rather than to the temperature of the evaporating means 28. The expansion of the bellows 92 is opposed by a compression type coil spring 98 which has its tension adjusted by a finger knob 100 by which the temperature at which the bellows moves the mercury tube from one extreme position to the other may thus be adjusted.

In order to protect the motor 34 and particularly the running winding 38 from overloads and in order to use the mercury contacts for the overload contacts, I pivotally mount the pivot support bracket 68 upon the pin 113 which pivotally connects the bracket 68 to an ear provided upon the base 90. A tension type coil spring 117 connects a portion of the bracket 68 above the pivot pin 113 to a pin 119 so as to tend to turn the bracket 68 in a clockwise direction to the pivot pin 113. This will tilt the mercury tube 46 into the position shown in Fig. 2 so as to prevent the energization of the electric motor 34. The ratchet wheel solder pot device 52 normally prevents the movement of the bracket 68 to this position since it holds the pawl 121 provided on pivot support 68 so as to prevent clockwise movement of the pivot support 68 upon the pivot pin 113. When an overload occurs the heat given off by the current flowing in the coil around the solder pot ratchet wheel device 52 will heat the solder to permit the ratchet wheel to rotate and release the pawl 121 and the pivot support 68 to permit the pivot support 68 to rotate about the pivot 113 in order to move the mercury tube to the position shown in Fig. 2. The pivot support 68 is returned to its normal operating position after the solder congeals and again holds the ratchet wheel. This is done by manually operating the lever 123 which projects from the pivot support 68.

The control as shown in Fig. 1 shows the refrigerating system and its driving motor operating under normal running conditions. The mercury tube 46 is in the position shown in Fig. 4 and only the running winding 38 is energized. When the evaporating means 28 is sufficiently cool, the pressure within the bellows 92 will be lowered sufficiently to enable the spring 98 to

force the primary lever 84 downwardly to throw the lever portion of bracket 64 across its dead center so that the mercury tube is moved to the position shown in Fig. 2, thereby stopping the operation of the motor and the refrigerating system.

When the evaporator 28 again warms up, the pressure within the bellows 92 will become sufficiently great to overcome the tension of the compression spring 98 and the toggle spring 76 to move the mercury tube 46 back to the position shown in Fig. 1. When the mercury tube is moved to the position shown in Fig. 1 the mercury will be disposed as shown in Fig. 3, with a portion of the mercury being held by the dam in contact with the starting winding contact 58, while another portion is in contact with the other two contacts 44 and 56. The mercury flowing through the orifice 62 will connect the two pools of mercury so that both the main contact 56 and the starting contact 58 will be connected or bridged electrically to the power supply contact 44. This will make it possible for the motor to start. The amount of mercury held behind the dam 62, as shown in Fig. 3, together with the size of orifice determines the length of time the starting winding is energized since this determines the length of time the mercury remains in contact with the contact 58 as shown in Fig. 3. It is only necessary that the starting winding remain energized a very short length of time allowing the motor to begin to rotate and to attain some speed. The mercury will rather quickly flow through the orifice 62 to the lower end of the mercury tube 46 so that it will then be dis-

posed as shown in Fig. 4 which is the normal running position.

Since the mercury contacts make no noise this control is very quiet. The snap acting mechanism may be made with a very light toggle spring and the stops 70 and 72 may be cushioned so as to minimize the noise from this source. It will be seen that this control is simple, efficient and reliable, and it is also exceptionally quiet.

While the form of embodiment of the invention as herein disclosed, constitutes a preferred form, it is to be understood that other forms might be adopted, all coming within the scope of the claim which follows:

15 What is claimed is as follows:

Control means for an electric motor having starting and running windings connected to one side of a source of current comprising in combination, a sealed tube partially filled with electric conducting fluid, said sealed tube being provided with an electrode adapted to be connected to said starting winding, said sealed tube being provided with a second electrode adapted to be connected to the running winding and a third electrode adapted to be connected to the other side of a source of current for energizing said windings, means for tilting the tube, and means within said tube whereby upon tilting the tube in the one direction the circuit is first closed between said third electrode which is connected to said source of current and said starting and running winding electrodes and is subsequently opened to the starting winding after a predetermined time interval.
